UNITED STATES PATENT OFFICE.

HARRY W. KARN, OF PITTSBURGH, PENNSYLVANIA.

ARTIFICIAL LIMB.

1,258,908.

Specification of Letters Patent. Patented Mar. 12, 1918.

Application filed June 30, 1917. Serial No. 178,050.

To all whom it may concern:

Be it known that I, HARRY W. KARN, a citizen of the United States, residing at Pittsburgh, in the county of Allegheny and State of Pennsylvania, have invented certain new and useful Improvements in Artificial Limbs, of which the following is a specification.

This invention refers to improvements in artificial limbs, more especially an artificial articulated leg, consisting of an upper thigh portion adapted to form a receiving connecting receptacle for the stump of the human leg, and having a lower portion pivotally connected to turn at the knee joint.

The improvement consists in mechanism by which the lower limb member may be operated on its pivot by the user, and the invention is constructed and adapted to operate in the manner more fully herein-after described.

Referring to the drawings:

Figure 1 is a general view in elevation showing the device as applied to the body. Fig. 2 is an enlarged vertical sectional view showing the compound leg member detached from the body.

Fig. 3 is an enlarged perspective view of the operating lever mechanism. The artificial leg members A, B, are of generally usual construction, made of wood or other suitable light strong material, the member A having at its upper portion a receiving terminal a adapted to fit closely around the stump of the amputated limb and to be held thereon by the tension of the supporting and connecting elements, hereinafter described.

The lower member B is pivotally connected by bolt 2 with the upper member A in a well-known manner whereby the two members are articulated to provide the knee joint. The lower outer front portion of the upper member A is rounded as indicated at 3 and fits neatly within the upper front edge portion 4 of the member B, providing for a small overlapping extension of each member at varying positions.

An operating lever member 5 is mounted on the pivot 2 and comprises a downwardly extending portion 6 and a forwardly extending portion 7 extending from the upper end of the portion 6 and at substantially right angles thereto. The downwardly extending portion is secured to the leg or lower member B by a sleeve or eye 8. The

under side of the portion 7 of the lever 5 is provided with a lateral slot 8a adjacent its forward end and a spring retaining member 9 is mounted adjacent the slot and extends over the said slot to normally close the same.

A U-shaped member 10 is mounted within the slot 8 and has its free ends bent forming hooks 11 which are adapted to receive strap members 12, which pass outwardly through apertures 13 in the portion A of the limb and are provided adjacent their free ends with sheave pulleys 14 provided with guards 15. The straps 12 it will be noted do not bear on any surface of the limb and therefore do not create friction.

I provide two such straps 12 each of which is connected to one of the hooks 11 formed on the member 10, so that when the cords 12 are relaxed the member B may fall to a vertical position as indicated in Fig. 2. When the cords 7 are drawn upwardly the lever member 5 will be rocked upon its pivot 2 and the member B may be erected or raised into longitudinal alignment with member A.

For the purpose of connecting straps 12 and their associated mechanism with shoulder-actuated operative mechanism, I use a pair of cords 16, each of which is provided at the front with a ring or other suitable connecting device 17, and at the back with a similar ring or connecting device 18. Cords 16, being continuous from each such ring 17 to the other ring 18, are thus free to engage with varying degrees of tension the sheaves 10 and to exert a pulling action on one or the other of the straps 12 independently.

For the purpose of transmitting independent active tension to one strap 12 or the other, I utilize independent suspender straps or braces 19 and 20, respectively, adapted to pass over the left and right shoulder respectively of the wearer, as shown in Fig. 1 and provided with suitable buckles 21 or other means for taking up slack. Each cord 16 is preferably passed through a suitable keeper or guiding and retaining loop device 22 at the front and 23 at the back upper portion of the main upper limb member A so as to retain the cords in operative position on the outer portion of the limb at the front and back.

The construction and operation of the device will be readily understood from the

foregoing description. Shoulder braces 19 and 20 are actuated, either one or the other, by the user, by raising one shoulder or the other, thereby exerting a lifting tension 5 through the straps 12 and rocking the lever 5 upon the pivot 2, which will thereby pull the lower leg section B forward, lowering of the shoulder correspondingly effects a lowering of the limb by gravity to a natural 10 position of repose.

Although I have shown and described one particular and preferred form of my invention, it will be understood that I do not wish to be limited thereto, since various 15 changes in design, and structural details may be made within the scope of the appended claims, without departing from the spirit of my invention.

What I claim is:

20 1. The combination of a thigh and a leg section pivotally connected together, a knee-bolt extending through said thigh and leg sections at said pivotal connection, a bell crank lever mounted on said bolt, said lever 25 extending from the thigh portion into the leg portion, a sleeve secured to the leg-section and engaging said lever, the upper portion of said lever having a recess therein adapted to receive a substantially U-shaped 30 member, said U-shaped member having its free ends bent to form retaining hooks, a strap engaging each of said hooks and extending upwardly within the thigh member and through apertures to the outside thereof 35 and provided with a terminal sheave wheel, and means engaging said sheaves adapted to rock said lever and move said leg section upon its knee pivot.

2. The combination of a thigh and a leg 40 section pivotally connected together, a knee-bolt extending through said thigh and leg sections at said pivotal connection, a bell crank lever mounted on said bolt, said lever

extending from the thigh portion into the leg portion, a sleeve secured to the leg-section and engaging said lever, the upper portion of said lever having a recess therein adapted to receive a substantially U-shaped member, said U-shaped member having its free ends bent to form retaining hooks, a 50 spring retaining member mounted on said lever and normally closing the opening to said recess to lock said U-shaped member in position, and means connected to said U-shaped member adapted to rock said lever 55 and move said leg section upon its knee pivot.

3. An artificial limb of the class described comprising a thigh member, a lower leg member, a knee pivot passing through said members, a bell crank lever member mounted on said pivot having a recess in the under side of its upper arm, a substantially U-shaped member engaging said recess, said U-shaped member having its free ends bent to form hooks, and means engaging said hooks for rocking said lever member and said lower leg member.

4. In combination with an artificial limb of the class described having a thigh member, a lower leg member, and a knee bolt passing through said members; a bell crank lever member mounted on said bolt and engaging said lower leg member, said lever having a recess in its upper arm, a substantially U-shaped member mounted within said recess, said U-shaped member having its free end bent to form hooks, means for retaining said U-shaped member in said recess, and means connected to said hooks 75 adapted to actuate said lever and said lower leg member.

In testimony whereof I hereunto affix my signature.

HARRY W. KARN.
